APPARATUS FOR TEMPERATURE
REGULATION

Martin Frisch, New York, N. Y., assignor to Foster Wheeler Corporation, New York, N. Y., a corporation of New York

Application August 30, 1946, Serial No. 694,116

5 Claims. (Cl. 122—479)

1

This invention relates to temperature regulation and more particularly pertains to the control of the temperature of superheated vapor.

The present invention provides a method and apparatus for controlling the temperature of superheated vapor by desuperheating the same through the introduction of condensate thereinto which condensate is produced by condensing a portion of the purified vapor before its introduction into the superheater. The condensate is produced, in the present invention, at a point prior to the point of introduction of the vapor into the inlet of the superheater. The condensate consists partially of minute droplets in suspension in vapor, which is introduced into the inlet of the superheater, and partially of liquid condensate which is introduced into the superheater at an intermediate point. Thus the final vapor temperature may be controlled, or it may be maintained constant under varying loads imposed on the generator, by controlling the amount of condensed vapor delivered to the superheater.

The invention will be disclosed as applied to the control of temperature of superheated steam but it will be understood that the invention is capable of application to the temperature control of vapors generally.

In accordance with the embodiment of the present invention disclosed, steam is condensed by a condenser in the inlet header of a superheater. The condensate collected in the lower portion of said header is conducted to an intermediate header connected to the superheater intermediate the inlet and outlet thereof while steam with suspended droplets of water entrained therein is conducted from the upper portion of the inlet header to the inlet end of the superheater tubes. The condensate is thereby distributed over a large portion of the superheater and the condensate introduced into the intermediate header will be vaporized in the superheater within a relatively short distance. With the present invention, the superheated steam temperature is controlled by adding chemically pure condensate to the steam. The amount of condensate introduced into the steam is governed by controlling the flow of condensing medium through the condensing surface thereby governing the temperature of the surface.

The invention will be understood from the following description when considered in connection with the accompanying drawings in which:

Fig. 1 is a more or less diagrammatic representation of a steam generator in partial vertical section embodying a preferred form of the invention, and

2

Fig. 2 is a sectional view taken on the line 2—2 of Fig. 1.

Like characters of reference refer to the same or similar parts throughout the views.

5 Referring to the drawings, the reference numeral 10 designates the setting of the upper part of a steam generator having a combustion chamber 11 fired by burner means, not shown, and comprising a main upper steam and water drum 12 and another upper drum 13. The drums 12 and 13 are connected by a group of steam circulator tubes 14 and a group of water circulator tubes 14'. Upper drum 12 is in communication with lower water drum 15 through a bank of steam generating tubes 15' with which gases of combustion from the chamber 11 flow in heat exchange relationship. Circulator tubes 16 connect the lower drum 15 with the upper drum 13. Feed water is delivered to the drum 12 through a feed water pipe 17 controlled by a valve 18. 10 In the form of the invention shown, a steam purifying device such as a steam dryer 19 is disposed within the steam space of the drum 12, while the purified steam is withdrawn from said drum through saturated steam outlet conduits 20. 15 20 A superheater 21 is positioned within a gas pass or heating zone 21' which is bounded in part by the bank of steam generating tubes 15' and the circulator tubes 16 and 14'. Superheater 21 comprises a plurality of inlet tubes 22 connected at one end to an inlet header 23 and at the opposite end to an intermediate header 24. The inlet tubes 22 are connected to the upper portion of the inlet header 23 and extend downwardly into the heating zone 21' thence upwardly to the intermediate header 24 where they are connected to the lower part of said header. A plurality of outlet tubes 25 comprise an outlet section of the superheater 21 which tubes are connected at one end thereof to the lower portion of the intermediate header 24 and extend downwardly into the heating zone 21' thence upwardly to an outlet header 26. Gases of combustion flow in heat exchange relationship with the superheater 21 in passing from the combustion chamber 11 through the heating zone 21' to the tube bank 15 which gases, after flowing in heat exchange relationship with the tube bank 15, pass outwardly from the setting 10 through a gas outlet passage 50.

40 Inlet header 23 receives saturated steam through saturated steam lines 20 and is provided with condensing surface 27 which, as shown, comprises a group of return bend tubes 45 28, the inlet ends of which are in communica-

tion with an inlet chamber 29 (Fig. 2) which receives condensing medium through conduit 30. The outlet ends of the tubes 28 are in communication with an outlet compartment 31 having an outlet through outlet conduit 32. Conduit 32, as shown, is in communication at its opposite end with feed water conduit 17. Condensate is conducted from the inlet header 23 to intermediate header 24 by drain tubes 33, one end of which tubes are connected to the lower portion of the inlet header. The opposite end of the drain tubes is connected to an atomizing nozzle 33' which nozzle is in communication with the intermediate header 24 so that condensate in an atomized state is introduced thereinto.

Flow of condensing medium through conduit 30 to tubes 28 of condensing surface 27 is controlled by a valve 34. As shown, operation of valve 34 is controlled in response to temperature changes in the superheated steam leaving superheater outlet header 26 through the superheated steam outlet conduit 35. Such temperature changes are transmitted from the outlet conduit 35 through line 36 to Sylphon bellows 37 connected to one end of lever arm 38 which operates a pilot valve 39. Lever arm 38 is connected at its end by links 40 and 41 to rod 42 of a piston 43 which moves in a relay cylinder 44. Fluid, such as oil which normally fills the relay cylinder, is led to pilot valve 39 through a feed tube 45 and is permitted to flow from the valve either through tube 46 to the upper portion of the cylinder 44 above the piston 43, or through tube 47 to the lower portion of the cylinder, the different paths of flow being controlled by the position of valve 39. Valve 34 in conduit 30, which conducts cooling water to the condenser 27, is connected to piston 43 through a lever arm 48.

In operation, steam entering the drum 12 will be dried or otherwise purified by passing through the dryer 19 and will be conducted through conduits 20 to inlet header 23 wherein part of the steam will be condensed by indirect contact with water flowing through the tubes 28 from the conduit 30. Condensate produced in inlet header 23, which condensate consists partially of minute droplets in suspension in the steam and partially of liquid formed on the condensing surface 27 and which passes to the lower portion of the inlet header in a liquid phase, is delivered to the superheater 21 in two portions. The portion which consists partially of minute droplets in suspension in steam passes outwardly of the header 23 at the upper portion thereof and enters the superheater tubes 22 flowing downwardly therein then upwardly to enter the intermediate header 24, this portion of the condensate being vaporized in the tubes 22. The liquid portion of the condensate flows downwardly from the lower portion of the inlet header 23 through tubes 33 thence into the atomizing nozzles 33' and, in an atomized state, into the intermediate header 24. The liquid condensate mixes with and is evaporated by the steam partially superheated in the tubes 22 and acts to desuperheat said steam. Because of the difference in temperature between said steam and the condensate, the evaporation on the condensate will occur within a relatively short distance in the superheater tubes 25 into which the mixture flows from header 24. The flow of steam through tubes 22 will be continuous due to the natural pressure drop from the inlet header 23

5 to the intermediate header 24. Steam superheated in the tubes 25 enters the outlet header 26 and passes into the superheater steam outlet conduit 35.

When the temperature of the steam leaving the superheater through conduit 35 exceeds a predetermined value, the temperature measuring device 36 causes the bellows 37 to expand downwardly to connect the oil flow path 47 with the valve discharge. The balance in the relay cylinder 44 is thereby changed and the piston 43 and rod 42 are moved upwardly opening the valve 34. An additional amount of cooling water will flow through the condenser tubes 28 and a greater amount of liquid condensate will be produced in the superheater inlet header 23 with the result that more condensate will flow to the intermediate header 24 thereby reducing the final temperature of the superheated steam until the desired steam temperature is attained. If the temperature of the superheated steam falls below a predetermined value, the operation will be reversed. The temperature controller will operate to move valve 34 toward closed position until the temperature of the steam has been increased to the predetermined value. During operation feed water is always available in adequate quantities through line 17 in which the valve 18 may be controlled in any desired manner.

Any suitable type of condenser or condensing equipment may be utilized. Moreover, the invention is not limited in its application to any particular type of steam or vapor generator.

Inasmuch as various changes may be made in the form, location and arrangement of the parts of the apparatus disclosed and in the steps of the process and their sequence as disclosed without departing from the principles of the invention, it will be understood that the invention is not to be limited excepting by the scope of the appended claims.

What is claimed is:

1. Apparatus for superheating vapor comprising a superheater having an inlet header, an intermediate header and an outlet header, superheater tubes connecting the inlet header and the intermediate header, other superheating tubes connecting the intermediate header and the outlet header thereby forming a flow path from the inlet header to the outlet header, said superheater tubes and said other superheater tubes being disposed in heat exchange relationship with heated gases, a condenser in the inlet header, means for supplying a condensing medium to the condenser, means for passing unsuperheated vapors into the condenser so that said vapors flow in heat exchange relationship therewith to produce condensate and to produce a mixture of vapor and liquid, means for controlling the quantity of unsuperheated vapor condensed, and conduit means in communication with the lower portion of the inlet header and with the intermediate header through which condensate is conducted from the inlet header into the intermediate header so as to introduce condensate into the vapor flowing through the intermediate header, the inlet of said superheater tubes communicating with the upper portion of the inlet header to receive said mixture of vapor and liquid.

2. Apparatus for superheating vapor comprising a superheater having an inlet header, an intermediate header and an outlet header, superheater tubes connecting the inlet header and the intermediate header, other superheating tubes

connecting the intermediate header and the outlet header thereby forming a flow path from the inlet header to the outlet header, said superheater tubes and said other superheater tubes being disposed in heat exchange relationship with heated gases, a condenser in the inlet header, means for supplying a condensing medium to the condenser, means for passing unsuperheated vapors from a vapor generator out of heat exchange relationship with a heating medium to the condenser so that said vapors flow in heat exchange relationship with the condenser to produce condensate and to produce a mixture of vapor and liquid, means for controlling the quantity of unsuperheated vapor condenser in response to the temperature of the vapor after heating in the superheater, and conduit means in communication with the lower portion of the inlet header and with the intermediate header through which condensate is conducted from the inlet header into the intermediate header so as to introduce condensate into the vapor flowing through the intermediate header to thereby control the temperature to which the vapor is heated, the inlet of said superheater tubes communicating with the upper portion of the inlet header to receive said mixture of vapor and liquid.

3. Apparatus for superheating vapor comprising a superheater having an inlet header, an intermediate header and an outlet header, superheater tubes connecting the inlet header and the intermediate header, other superheater tubes connecting the intermediate header and the outlet header thereby forming a flow path from the inlet header to the outlet header, said superheater tubes and said other superheater tubes being disposed in heat exchange relationship with heated gases, a condenser in the inlet header, means for supplying a condensing medium to the condenser, means for passing unsuperheated vapors into the condenser so that said vapors flow in heat exchange relationship therewith to produce condensate and to produce a mixture of vapor and liquid, means for controlling the quantity of unsuperheated vapor condensed, conduit means connecting the lower portion of the inlet header and the intermediate header through which condensate is conducted between the inlet and intermediate headers so as to introduce condensate into the vapor flowing through the intermediate header, and atomizing means in communication with said conduit means and the intermediate header to atomize the condensate entering said intermediate header, the inlet of said superheater tubes communicating with the upper portion of the inlet header to receive said mixture of vapor and liquid.

4. A steam generator comprising a steam generating section including a steam drum, a superheater having an inlet header, an intermediate header and an outlet header, superheater tubes connecting the inlet header and the intermediate header and other superheating tubes connecting the intermediate header and the outlet header thereby forming a flow path from the inlet header to the outlet header, said superheater

tubes and said other superheater tubes being disposed in heat exchange relationship with gases of combustion of the steam generator, a condenser in the inlet header, means for supplying a condensing medium to the condenser, means for passing steam from the steam drum out of heat exchange relationship with a heating medium to the inlet header wherein said steam passes in heat exchange relationship with the condenser to produce condensate and to produce steam having minute water droplets in suspension therein, means for controlling the quantity of steam condensed in response to the temperature of the steam after superheating, conduit means in communication with the lower portion of the inlet header and with the intermediate header through which condensate is conducted from the inlet header to the intermediate header so as to introduce condensate into the vapor flowing through the intermediate header, and atomizing means in communication with the conduit means and the inlet header to introduce said condensate into the intermediate header in an atomized state, the inlet of said superheater tubes communicating with the upper portion of the inlet header to receive said steam having minute water droplets therein.

5. Apparatus for superheating vapor comprising a superheater disposed in heat exchange relationship with heated gases and having an inlet portion and an outlet portion, said inlet portion and said outlet portion being in communication with one another through an intermediate header so that vapor from the inlet portion flows to the outlet portion through said header, a condenser, means for supplying a cooling medium to the condenser, means for passing unsuperheated vapors into the condenser so that said vapors flow in heat exchange relationship therewith to produce condensate and to produce a mixture of vapor and liquid, conduit means in communication with the condenser and the superheater for introducing said mixture into the inlet portion of the superheater, other conduit means separate from said conduit means and in communication with the condenser so as to receive condensate therefrom and in communication with the intermediate header so as to introduce condensate into the vapor flowing through the intermediate header, and means for controlling the quantity of vapor condensed.
